UNITED STATES PATENT OFFICE

163,282

MOTOR STETHOSCOPE OR THE LIKE

Eugene A. Heschel, Vickery, Ohio, assignor to The
Bingham-Herbrand Corporation, Toledo, Ohio,
a corporation of Ohio

Application January 9, 1950, Serial No. 7,096

Term of patent 14 years

(Cl. D54—13)

To all whom it may concern:

Be it known that I, Eugene A. Heschel, a citizen of the United States, and resident of Vickery, in the county of Sandusky, and State of Ohio, have invented a new, original, and ornamental Design for a Motor Stethoscope or the like, of which the following is a specification, reference being had to the accompanying drawing, forming a part thereof.

In the drawing, Fig. 1 is a perspective view of a motor stethoscope or the like showing my new design;

Fig. 2 is a fragmentary side elevational view; and

Fig. 3 is an end view taken from the right of Fig. 2.

The dominant features of my design reside in the portions shown in full lines.

I claim:

The ornamental design for a motor stethoscope or the like substantially as shown and described.
EUGENE A. HESCHEL.
